UNITED STATES PATENT OFFICE.

BERNARD SHELDON, OF KEYPORT, NEW JERSEY.

PENCIL.

Application filed September 27, 1923. Serial No. 665,117.

To all whom it may concern:

Be it known that I, BERNARD SHELDON, a citizen of the United States, and residing at Keyport, in the county of Monmouth and State of New Jersey, have invented certain new and useful Improvements in Pencils, of which the following is a specification, such as will enable those skilled in the art to which it appertains to make and use the same.

This invention relates to pencils and particularly to adjustable lead feeding pencils, and the object of the invention is to provide a pencil of the class specified composed of a main tubular body and a lead carrying and feeding member movable longitudinally of said body with means rotatably mounted in connection with one end portion of the body for operating said member, said member being tubular in form to provide for the storage of extra leads; and with these and other objects in view, the invention consists in a device of the class specified which is simple in construction and operation and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of a pencil made according to my invention.

Fig. 2 is a section on the line 2—2 of Fig. 1.

Fig. 3 is a section on the line 3—3 of Fig. 1; and,

Fig. 4 is a section on the line 4—4 of Fig. 1.

In carrying my invention into effect, I provide a main tubular body portion 5, one end of which is conical in form as shown at 6 and provided with a small discharge aperture 7. The bore of the body 5 is provided on opposite sides with longitudinal grooves 8 and the upper end portion of the body is curved outwardly and inwardly to form a beaded flange portion 9 which is cut at predetermined intervals as shown at 10 to form separate spring members 11. Mounted in the body 5 is a tubular member 12 which is tapered as shown at 15 to fit within the tapered portion 6 of the body 5, and the end of the tapered portion 15 is split and apertured to form a clamp portion

16 for receiving and frictionally retaining a piece of lead 17 in connection therewith. The member 12 together with the plug 14 constitutes a lead feeding element and is provided at the lower end of the member 12 with laterally directed extensions 18 which operate in the grooves 8 of the body 5 to permit of the longitudinal movement of the member 12 in said body. The member 12 or the chamber 19 therein is adapted to receive a number of additional leads 17 as clearly shown in Fig. 1 of the drawing.

The periphery of the member 12 is threaded as shown at 20 to engage a threaded portion 21 on a rotatable member 22 mounted in the upper end portion of the body 5. The member 22 is tubular in form and the upper end of which projects beyond the body 5 and is closed by a head or cap portion 23, beneath and at a predetermined distance from which the periphery of the member 22 is provided with an annular bead 24 in connection with which the beaded portion 9 operates to frictionally retain the member 22 in connection with the body 5.

In the position of the parts shown in Fig. 2, it will be understood that the lead 17 mounted in the holder or plug part 14 has been fully or substantially fully extended and in order to insert a new lead the member 22 is rotated to move the member 12 upwardly into the member 22, and longitudinally of the body 5, after which the member 22 is removed from the body 5 by holding the body 5 in one hand and pulling on the member 22 to release the bead 24 from the spring beaded portion 9. The plug 14 is then removed and one of the members 17 within the member 12 removed and placed in the spring jaw 16, after which the members 12 and 22 are again placed in the body 5 and the member 22 is rotated to project the new lead a slight distance beyond the tip or pointed end of the body 5. As the lead is worn down, the same is fed outwardly by the rotation of the member 22 in one direction.

From the foregoing, it will be apparent that my improved pencil is composed of four parts, namely the body 5, the tubular member 12, the plug 14 mounted in connection with the member 12 and the rotatable member 22. By reason of the simplicity of the construction of the pencil, the same may be produced at a nominal cost, and yet a strong and durable pencil is provided.

It will be understood that while I have shown a specific form of construction for carrying my invention into effect, that I am not necessarily limited to the details of construction herein shown and described, and various changes therein and modifications thereof may be made within the scope of the appended claims without departing from the spirit of my invention or sacrificing its advantages.

Having fully described my invention, what I claim as new and desire to secure by Letters Patent, is:—

1. A pencil of the class described comprising a tubular body portion, a member rotatably mounted in connection with one end portion thereof, means for retaining said member in predetermined position with reference to said body, a lead feeding member in threaded engagement with said rotatable member and keyed to said body portion whereby the rotation of said first named member will move the second named member longitudinally of said body portion, said second named member being tubular in form and provided therein with a storage chamber for leads, and a plug controlling the admission to said chamber, said plug being provided at its free end with means for receiving and frictionally supporting a lead.

2. A pencil of the class described comprising a tubular body portion, one end of which is conical in form and provided with a lead discharge aperture, said body portion being provided with longitudinal keyways, an externally threaded sleeve mounted in said body portion and provided with parts extending into said keyways to prevent the rotation of said sleeve in said body portion and permitting of longitudinal movement therein, the other end portion of the tubular body

being open, a tubular member rotatably mounted in connection with said end of the body and in threaded engagement with said externally threaded sleeve, and means detachably mounted in connection with and adapted to support a piece of lead in connection with said externally threaded member and in axial alignment with the aperture in said body portion, said last named means also serving to retain extra leads within said sleeve.

3. A pencil of the class described comprising a tubular body portion, one end of which is conical in form and provided with a lead discharge aperture, said body portion being provided with longitudinal keyways, an externally threaded sleeve mounted in said body portion and provided with parts extending into said keyways to prevent the rotation of said sleeve in said body portion and permitting of longitudinal movement therein, the other end portion of the tubular body being open, a tubular member rotatably mounted in connection with said end of the body and in threaded engagement with said externally threaded member, means detachably mounted in connection with and adapted to support a piece of lead in connection with said externally threaded member and in axial alignment with the aperture in said body portion, means for frictionally retaining the body portion and said rotatable member in predetermined relation, and said externally threaded member being provided with a lead storage chamber, closed by said lead supporting means.

In testimony that I claim the foregoing as my invention I have signed my name this 25th day of Sept. 1923.

BERNARD SHELDON.
